UNITED STATES PATENT OFFICE.

WILLIAM J. FORREST, JR., OF KENOSHA, WISCONSIN.

ELECTRICAL INDICATOR.

SPECIFICATION forming part of Letters Patent No. 770,230, dated September 13, 1904.

Application filed November 30, 1903. Serial No. 183,221. (No model.)

To all whom it may concern.

Be it known that I, WILLIAM J. FORREST, Jr., a citizen of the United States, residing at Kenosha, in the county of Kenosha and State 5 of Wisconsin, have invented a new and useful Electrical Indicator, of which the following is a specification.

This invention relates to certain improvements in indicators of that general class in 10 which a disk or similar element receives a step-by-step movement to consecutively display numerals, characters, or other symbols through a common display-opening.

The principal object of the invention is to 15 provide a device for use in barber-shops and other places to indicate the order in which customers are to be attended to, each person entering the shop being furnished with a ticket bearing a numeral and the indicator being 20 operated each time a customer is attended to and his ticket collected, so that the waiting customers may be informed of their proper turns.

The invention is of course applicable to 25 devices of any class, such as those employed for counting or on cars or trains for indicating successive street-crossings or stations.

A further object of the invention is to provide an electrically-actuated indicator in which 30 the indicating disk or disks will be positively locked after each movement, and thus prevent any irregularity in the movement of the disk on the sudden impulse of the armature when attracted by the operating-magnet.

35 With these and other objects in view the invention consists in the novel construction and arrangement of parts hereinafter described, illustrated in the accompanying drawings, and particularly pointed out in the appended claims, it being understood that various changes in the form, proportions, size, and minor details of the structure may be made 40 without departing from the spirit or sacrificing any of the advantages of the invention.

45 In the accompanying drawings, Figure 1 is a rear elevation of an electrical indicator constructed in accordance with the invention. Fig. 2 is a similar view of a portion of the

same, showing the parts in slightly-different position. Fig. 3 is a front elevation showing 50 the manner in which the numbers or other symbols are displayed. Fig. 4 is a front elevation showing a form of advertising-casing in connection with which the indicator may be used. 55

Similar numerals of reference are employed to indicate corresponding parts throughout the several figures of the drawings.

In the drawings, 1 indicates a suitable base having bearings for the reception of parallel 60 shafts or studs 2 and 3, on which are mounted indicating-disks 4 and 5, respectively, the outer faces of the disks bearing the numerals or other symbols to be displayed through an opening 6, formed in a face-plate 7. In the 65 present instance each disk is provided with an annular row of numerals, from "1" to "9" and "0," and these may be brought successively in alignment with the display-opening to indicate numbers from "1" to "99." 70 When used in a barber-shop or other public place, the casing may be in the form of an ornamental frame and utilized in part as an advertising medium, as indicated in Fig. 4.

On the rear end of the shaft 2 is secured a 75 ratchet-wheel 8, having a number of teeth equal to the number of divisions of the disk—ten in the present instance—and bearing on these teeth is one end of a spring 9, that serves to retard the movement of the disk and at the 80 same time acts to prevent any backward movement. The face of the ratchet-wheel is further provided with a series of projecting pins 10, that form a part of the stop-motion for limiting the turning movement of the disk. 85

To the rear of the supporting-base is secured a frame 11, that in part supports an electromagnet 12, and mounted on the frame is a lever 13, carrying an arm 14, arranged within the field of force of the magnet. Under 90 normal conditions the magnet is deenergized, and the armature is held away from the pawls by means of a spring 15. At the upper end of the lever 13 is pivoted a pawl 16, adapted to engage the teeth of the ratchet-wheel 8, and each time the magnet is ener- 95

gized its armature will be retracted and the pawl will be moved to the extent of a single tooth of the ratchet-wheel, and when the magnet is deenergized the pawl will be moved 5 back to initial position and engage a succeeding tooth in readiness for the next operation.

To the frame 11 is pivoted a two-armed lever 17, connected at one end to the lever 13 by means of a link 18. The opposite arm of 10 the lever is connected at the rear end of a stop-finger 19, adapted to a suitable guide 20 on the rear portion of the frame and so disposed that each time the electromagnet is energized the stop-finger will be forced in the 15 direction of the ratchet-wheel and by contact with the pins 10 will serve to correct the movement of the disk and at the same time positively lock the disk in place. On the operating movement of the pawl the finger will be 20 withdrawn from engagement with the pins 10 and leave the disk free to revolve.

The secondary or transfer disk 5 is provided with rearwardly-projecting pins or studs 23 of a number equal to the number of divisions 25 on the disk—ten in the present instance. These pins are successively engaged by a radially-projecting finger 24, carried by the disk 4, the finger coming into contact with one of the pins at the completion of each rotative movement 30 of the main disk 4. This serves to operate the secondary disk, so that when the primary disk moves from "9" the finger 24 will engage the secondary disk and move it from "0" to "1," so that the number at the 35 display-opening will be "10."

On the base 1 is secured a standard 25, to the upper end of which is pivoted a stop-lever 26, having a notch 27 for engagement with the successive pins 23, and said lever is 40 normally held in engagement with one or other of the pins by means of a small coiled compression-spring 28. The lever is further provided with a projecting shoulder 29, so disposed as to be engaged by the finger 24 in 45 advance of the contact of the latter with one of the pins. In the operation of this portion of the mechanism the finger 24 first comes into contact with the shoulder 29 and moves the stop-lever downward and in the direction 50 of the standard 25, so that the pin 23 will be released from notch 27. Further movement of the disk 4 and finger 24 will cause the latter to engage the pin 23 and move the same for an angular distance of thirty-six degrees, 55 or one-tenth of a revolution. The shoulder is first released from the standard, and before the movement of the disk is completed said lever reassumes its initial position in readiness to catch the next succeeding pin, and thus 60 stop the disk in proper position.

The base-board is preferably provided with an electric bell 30, connected in series or multiple by wires 31 to a source of electrical

energy, in the present instance indicated by a battery 32, and any desired number of circuit closers may be employed, so that the indicator may be operated from different points, as from each chair in a barber-shop. 65

Having thus described the invention, what is claimed is—

1. In an indicator, an indicating-disk, a ratchet-wheel connected thereto, a plurality of stop-pins projecting from the ratchet-wheel, a pivoted pawl-carrying lever, a pawl for engaging the teeth of the ratchet-wheel, a stop-finger connected to the lever and movable in a direction opposite to that of the pawl to engage the stop-pins during operative movement of said pawl, and means for actuating said pawl-carrying lever. 75

2. In an indicator, an indicating-disk, a ratchet-wheel connected thereto, a plurality of stop-pins projecting from the ratchet-wheel, a pivoted pawl-carrying lever, a pawl carried thereby and serving to engage the teeth of the ratchet-wheel, a stop-finger for engaging the pins, a support for said stop-finger, mechanism connecting the stop-finger to the pawl-carrying lever to transmit to said finger a movement in a direction opposite to that of the pawl, and means for actuating said pawl-carrying lever. 85

3. In an indicating mechanism, a revoluble disk, a ratchet-wheel connected thereto, a plurality of stop-pins, a pawl for engaging the teeth of the ratchet-wheel, a pivotally-mounted pawl-carrying lever, a finger for engaging between the stop-pins, means for guiding and supporting said finger, a two-armed pivotally-mounted lever having one arm connected to the finger, a link connecting the opposite arm of the lever to the pawl-carrying lever, and means for actuating said pawl-carrying lever. 95

4. In indicating mechanism, a primary disk, a secondary disk, a plurality of pins projecting from the secondary disk, a pivoted stop-lever having a notch for the reception of successive pins and presenting an inclined surface for engagement by the pins, a spring tending to hold said stop-lever in position, said lever having a laterally-projecting shoulder, and an arm carried by the primary disk and serving by preliminary engagement with said shoulder to move the lever to unlocking position and on continued movement to engage the previously-locked pin and impart angular movement to said secondary disk. 105

5. In an electrical indicator, a base, a pair of disks carried thereby, a ratchet-wheel secured to the primary disk, a plurality of pins extending from the ratchet-wheel, a pawl for engaging the ratchet-wheel, a stop-finger serving to correct the movement of the disk by engagement with the pins, a pivoted lever carried by the frame and carrying the pawl, 115 an electromagnet, an armature carried by the 120

lever and disposed within the field of force of the electromagnet, a plurality of pins projecting from the secondary disk, a stop-lever for engaging the successive pins, and a finger carried by the primary disk and serving to engage the stop-lever and disconnect the same from the pin in advance of the engagement of the finger with said pin.

In testimony that I claim the foregoing as my own I have hereto affixed my signature in the presence of two witnesses.
